MERCURY BOILER LEVEL INDICATOR

Henry Stelling, Bayonne, N. J., assignor to The Babcock & Wilcox Company, Bayonne, N. J., a corporation of New Jersey

Application June 30, 1928, Serial No. 289,543

9 Claims. (Cl. 73—54)

This invention relates to a device that is particularly suitable for indicating the mercury level in a mercury boiler, but it is not restricted to this particular use. The device can indicate at a point 5 remote from a boiler, the liquid level in the boiler. The invention will be understood from the description in connection with the accompanying drawing illustrating a portion of a mercury boiler in section with an illustrative embodiment of 10 the invention attached thereto.

In the drawing, reference character 1 indicates a portion of a mercury boiler in which the normal mercury level is indicated by the line 2. The lower side or mercury space of the boiler 1 has 15 one limb of a U-tube 3 connected thereto and the other limb of the U-tube extends above the boiler 1 and terminates in a cock 4. A tube 5 connects the upper portion of the long limb of the U-tube 3 to an indicator 6.

20 A tube 7 connects the upper or vapor space of the mercury boiler 1 to the side of a cistern or container 8 that is provided with a removable plug 9 in its upper side for introducing mercury when desired. The cistern 8 is located above the 25 boiler 1 and the tube 7 is so arranged that as soon as the mercury in the cistern 8 reaches a predetermined level, it will begin to drain back into the boiler. The lower portion of the cistern 8 is connected by the tube 10 to a similar cistern 11 located at the same level as the cistern 8. An upwardly extending tube 12 is connected to the upper portion of the cistern 11 and terminates in a cock 13. A tube 14 extends from the cock 13 to the indicator 6.

35 The indicator 6 is provided with a glass portion 15 and the tubes 5 and 14 are connected in such a manner that the liquids filling these tubes are visible through the glass. Devices of this character are well known, and it is not thought necessary to describe the same in detail.

The mercury in the boiler 1 filling the same to the level 2 will also fill the U-tube 3 to the level 35 16 in the section 17 of the tube 3. The plug 9 is removed and a sufficient amount of mercury is introduced to fill the cisterns 8 and 11 and the tube 10 to the level shown by the solid lines 18 and 19 at which level the mercury will begin to drain into the boiler through the tube 7 that enters the cistern 8 at the desired point about half way 50 between its bottom and top. A sufficient amount of water is introduced through the cock 4 to fill the tube 3 from the cock 4 to the mercury level 16 and to fill the tube 5 to the line 20 near the middle of the indicator 6. A sufficient amount of 55 oil is introduced through the cock 13 to fill the

portion of the cistern 11 above the mercury level 19, the tube 12, and enough of the tube 14 to cause the contact line between the oil and water to reach the point 20'. The tube 5 is then full of water. The cock 4 is then closed. More oil is 60 added through the cock 13 to fill the tube 14 to this cock. The cock 13 is then closed. The cross section area of the opening in the section 17 and that in the indicator 6 are preferably made the same size so that a change in the level 16 will cause 65 an equal change in the level 20.

The operation is as follows: When the mercury level falls in the boiler 1, for example, to the line 2', there will be a corresponding fall of the mercury level 16 to a line 16'. This causes the 70 water in the upper portion of the long limb of the tube 3 to descend and the water to rise in the tube 5, thus causing the contact line 20 between the water and oil in the indicator 6 to fall to the line 20'. The oil descends in the tube 14 and 75 rises in the tube 12. At the same time, the mercury level in the cistern 8 is lowered to the line 18' and that in the cistern 11 rises correspondingly to the line 19' in accordance with the amount of oil that has been displaced. The static head due 80 to the differences in the mercury levels in the cisterns 8 and 11 is so slight that the lowering of the mercury level from the line 16 to the line 16' in the tube 3 is almost exactly the same as the amount of lowering of the level from the line 2 85 to the line 2' in the boiler 1, and consequently the lowering of the contact line between the water and oil in the indicator 6 from the line 20 to the line 20' is almost exactly the same as the amount by which the mercury level has been 90 lowered in the boiler. The reason for this is that the cross section areas of the cisterns 8 and 11 are so large in comparison to the cross section area of the section 17 of the tube 3 that a displacement of mercury from the line 16 to the 95 line 16' in the section 17 moves such a small volume of mercury that a corresponding change in the volume of mercury in the comparatively large cisterns 8 and 11 will not materially change the mercury levels in them. The tube 7 connecting 100 the mercury space of the boiler 1 to the cistern 8 keeps the two at the same pressure and if any vapors passing upwardly through the tube 7 are condensed in the cistern 8, the mercury will drain back into the boiler.

When the mercury level in the boiler 1 rises, for example, to the line 2'', the same will rise to the line 16'' in tube 3, thus causing the contact line 20 between the water and oil in the indicator 6 to rise to the line 20'', causing oil to flow 110

into the cistern 11 and lowering the mercury level to the line 19" which will not change the mercury level in the cistern 8 because the mercury will drain through the tube 7 into the boiler 5 1 after the level 18 is reached.

The vertical distance between the normal mercury level 2 in the boiler and the contact line 20 in the indicator 6 should preferably be to the distance between the levels 18 and 19 in the cisterns 8 and 11 and the line 20 in the indicator 6 inversely proportional to the specific gravity of water to oil that is in the tubes 5 and 14, so that all the liquids in the whole mercury level indicator system will be in complete balance at 15 normal mercury level in the boiler 1.

The change of contact between the oil and water in the indicator 6 that is visible through the glass 15 rises and falls in accordance with the rise and fall of the mercury level in the boiler 1 20 so that an observation of the indicator will show the amount of mercury in the boiler.

With this device the liquid level in a mercury boiler operating at a high pressure and temperature can be safely and accurately indicated. Ordinary level indicators would not be suitable because of the danger of the same breaking. This is especially true of glass indicators. The escape 25 of the liquid or vapor mercury caused by a broken indicator would be very dangerous.

30 I claim:

1. A mercury level indicator for a mercury boiler comprising two conduits forming a U-tube and containing contacting columns of non-miscible liquids other than mercury, a mercury containing cistern located above the mercury level in said boiler, and means to establish communication between said cistern and said boiler above the normal mercury level in said boiler, one of 35 said conduits being connected to said cistern and the other of said conduits being connected to the mercury space of said boiler.

2. A mercury level indicator for a mercury boiler comprising two conduits forming a U-tube and containing contacting columns of non-miscible liquids in which the contacting surfaces of 40 said liquids are movable to indicate the mercury level, means for establishing communication between the mercury space of the boiler and one of said conduits, a mercury containing cistern located above the mercury level in said boiler, means to establish communication between said cistern and said boiler above the normal mercury level in said boiler, the other one of said conduits being connected to said cistern, and a second cistern 45 interposed in the communication between said first-named cistern and the boiler.

3. In a mercury level indicator for a mercury boiler, two mercury containing cisterns, a connection between the lower portions of said cisterns, a connection from one of said cisterns to the mercury vapor space of the boiler, two conduits forming a U-tube and containing contacting columns of non-miscible liquids, one of said conduits being connected to the other one of said cisterns, the liquids in each of said columns 50 contacting with liquid mercury.

4. In a mercury level indicator for a mercury boiler, two mercury containing cisterns located

above said boiler, a connection between the lower portions of said cisterns, a connection from one of said cisterns to the mercury vapor space of the boiler, two conduits forming a U-tube and containing columns of non-miscible liquids, one 55 of said conduits being connected to the other one of said cisterns and the liquid in the other conduit contacting directly with liquid mercury.

5. In a mercury level indicator for a mercury boiler, two mercury containing cisterns, a connection between the lower portions of said cisterns, a connection from the normal mercury level of one of said cisterns to the mercury vapor space of the boiler, two conduits forming a U-tube and containing columns of non-miscible liquids, one 60 of said conduits being connected to the other one of said cisterns and the liquid in the other conduit contacting directly with liquid mercury.

6. In a mercury level indicator for a mercury boiler, two mercury containing cisterns, a connection between the lower portions of said cisterns, a connection from one of said cisterns to the mercury vapor space of the boiler, two conduits forming a U-tube and containing columns of 65 non-miscible liquids, one of said conduits being connected to the other one of said cisterns and the liquid in the other conduit contacting directly with liquid mercury, and means through which the contact point between said liquids may 70 be observed.

7. In a mercury level indicator for a mercury boiler, two mercury containing cisterns, a connection between the lower portions of said cisterns, a connection from one of said cisterns to the 75 mercury vapor space of the boiler, two conduits forming a U-tube and containing columns of non-miscible liquids, one of said conduits being connected to the other one of said cisterns and the liquid in the other conduit extending above 80 the normal mercury level in the boiler and contacting with liquid mercury.

8. In a mercury level indicator for a mercury boiler, two mercury containing cisterns, a connection between the lower portions of said cisterns, a connection from one of said cisterns to the mercury vapor space of the boiler, two conduits forming a U-tube and containing columns of 85 non-miscible liquids, one of said conduits being connected to the other one of said cisterns and the liquid in the other conduit contacting directly with liquid mercury, a chamber of enlarged section in one of said conduits and the other including means through which the contact point between said liquids may 90 be observed.

9. A mercury level indicator for a mercury boiler comprising two conduits forming a U-tube and containing contacting columns of non-miscible liquids other than mercury, a mercury containing cistern located above the mercury level in said boiler, and means to establish communication between said cistern and said boiler above the normal mercury level in said boiler, one of 95 said conduits being connected to said cistern and the other of said conduits being connected by 100 means of a U-tube to the mercury space of said boiler.

HENRY STELLING.
